UNITED STATES PATENT OFFICE.

THOMAS C. RICHARDS, OF WINSTED, CONNECTICUT.

DESIGN FOR A CURTAIN OR SHADE PULL.

SPECIFICATION forming part of Design No. 34,790, dated July 16, 1901.

Application filed May 17, 1901. Serial No. 60,778. Term of patent 7 years.

To all whom it may concern:

Be it known that I, THOMAS C. RICHARDS, a citizen of the United States, residing at Winsted, in the county of Litchfield and State of Connecticut, have invented and produced a new and original Design for a Shade or Curtain Pull, of which the following is a specification.

The accompanying drawing is a view in elevation of my shade or curtain pull.

As shown in the drawing, the leading or material feature of my design consists of a pull or handle A, of a trefoil shape, open in its center, the outer edge of the figure being made up of a series of continuous curves and the inner edge parallel with said outer edge.

A plate projects upwardly from the body A of the pull and has an ornamental outline

comprising semicircular figures, three of which are clustered at the upper end of the plate and two appear at diametrically opposite points on the edge of the plate. A rectangular figure is seen in the body of the plate.

Having described my invention, what I claim as new, and desire to secure by Letters Patent, is—

The design for a curtain or shade pull herein shown and described.

In testimony whereof I have signed my name to this specification in the presence of two subscribing witnesses.

THOMAS C. RICHARDS.
